UNITED STATES PATENT OFFICE.

HENRY LEFEBVRE, OF DOUGLAS, ARIZONA, ASSIGNOR OF ONE-HALF TO MANUEL ELIAS LUCERO, OF DOUGLAS, ARIZONA.

PUNCHING-MACHINE.

1,219,963.

Specification of Letters Patent.

Patented Mar. 20, 1917.

Application filed October 21, 1915. Serial No. 57,145.

To all whom it may concern:

Be it known that I, HENRY LEFEBVRE, a citizen of the United States of America, residing at Douglas, in the county of Cochise 5 and State of Arizona, have invented certain new and useful Improvements in Punching-Machines, of which the following is a specification, reference being had therein to the accompanying drawing.

This invention relates to punching machines and has for its object the production of a simple and efficient punching machine for facilitating the keeping of the twyers open to permit the air to pass freely into 15 the converter while the machine is in operation.

Another object of this invention is the production of a simple and efficient punching device which may be easily and conveniently 20 attached to a smelter so as to permit the punching bars to pass through the twyers and efficiently operate to keep the twyers free from obstruction.

With these and other objects in view, this 25 invention consists of certain novel combinations, constructions, and arrangements of parts, as will be hereinafter fully described and claimed.

In the accompanying drawings:—

Figure 1 is a top plan view of the apparatus.

Fig. 2 is a side elevation thereof.

Fig. 3 is an end elevation.

Fig. 4 is a longitudinal section taken on 35 line 4—4 of Fig. 1.

Fig. 5 is a section taken on line 5—5 of Fig. 4.

Fig. 6 is a horizontal section through a portion of the converter, showing the manner in which the punching bars extend therethrough.

Fig. 7 is a horizontal section through one of the plunger cylinders, showing the manner in which the same is supported upon the 45 supporting framework.

Fig. 8 is a transverse section through the frame and bar for supporting the punching bars.

Fig. 9 is a section taken on line 9—9 of Fig. 8.

Fig. 10 is a vertical section through one of the punching bars supporting members, showing the manner in which the punching bars are secured thereto.

Fig. 11 is a detailed perspective of one end 55 of the punching frame.

Fig. 12 is a transverse sectional view through the inner end of the punching frame, showing the manner in which the same is secured to the converter.

Fig. 13 is a section taken on line X—X of Fig. 10.

Referring to the accompanying drawings by numerals it will be seen that 1 designates the converter which is supported upon the 65 concrete or other suitable support 2. The converter 1 is adapted to be operated by means of a motor 3 carrying a driving shaft 4, which shaft 4 is provided with a worm screw 5 meshing with a worm wheel 6. The 70 worm wheel 6 is carried by a shaft 7, the shaft 7 carrying supporting rollers 8 as clearly shown in Fig. 2. Other idle rollers 9 are supported upon the base or support 2 for the purpose of supporting the converter 75 1, above described. The wheels or rollers 8 and 9 engage the supporting wheels 10 as illustrated clearly in Fig. 2.

The converter 1 is provided with the usual twyers 11 as illustrated in Fig. 4, through 80 which twyers 11 are adapted to extend the punching bars 12 and 37. The usual wind box 13 is employed and communicates with the twyers 11 by means of a communicating passage 14, as illustrated in Fig. 4.

The frame 15 is supported upon one side of the converter and is provided with a pair of side portions or rails 16 of a channel iron construction, each rail 16 carrying at its rear end a block 17, which block supports 90 an overhanging plate 18 which is securely held in engagement with the block 17 by means of a bolt 19. This plate 18 is adapted to firmly clamp over the transversely extending supporting bar 20 of the converter 95 for supporting the inner end of the frame 15

in engagement with the converter. It should be understood that the frame may be easily and conveniently removed from the converter 1 when so desired by means of releasing the plates 18 from the supporting bar 20 and detaching the turn-buckle supporting mechanism hereinafter described.

The forward ends of the frame 15 are arranged in converging relation, over which 10 ends fit the radiating arms 21 of the operating cylinders 22. These arms 21 are provided with rearwardly extending ears 23 for fitting in firm engagement with the frame 15, the ears 23 being secured to the 15 frame 15 by means of the rivets 24.

Two of these cylinders 22 are employed, one cylinder being placed above the other, as illustrated in Fig. 4 of the drawings and a piston 25 is placed within each cylinder 20 which piston engages piston rods 26 and 26' as illustrated in Fig. 4. The outer ends of the cylinders 22 are closed by means of the cylinder heads 27, illustrated in Fig. 4 of the drawings. Communicating pipes 28 25 are connected to a suitable source of air or water supply for supplying suitable driving power to the cylinders 22 for operating the piston heads 25. The pipes 28 communicate with the respective ends of the cylinders to 30 control the admission and discharge of water or air from the cylinders 22.

It should be understood that any suitable driving power may be employed for the purpose of operating the piston rods 26, 35 without departing from the spirit of the invention.

The frame 15 is provided upon each side thereof with an eye 29 and a turn-buckle rod 30 engages each eye 29, the upper end of 40 each turn-buckle rod 30 being provided with a hook 31 for engaging the eyes 32 formed upon the converter 1. It will therefore be seen that these turn-buckle rods 30 will constitute an efficient support or brace for the 45 frame 15 and when it is desired, the frame may be readily released from the converter by detaching the plates 18, as above described, and also the turn-buckle rods 30 for moving the frame 15 out of engagement 50 with the converter 1, thereby permitting the converter to be operated without being interfered with by the punching machine.

The frame 15 is provided upon one face thereof with an upper track 33 and a lower 55 track 32. The upper piston rod 26 engages a plurality of ears 34, which ears are carried by a transversely extending bar 35 having its ends traveling in the track 33. A plurality of heads 36 are suspended below the 60 upper bar 35 and a punching rod 37 is supported upon each head 36, being firmly held in engagement therewith by means of the clamping bolts 38. The heads 36 are held

in detachable engagement with the bar 35 65 by means of the nuts 39 which are threaded upon the bolts 40 of the heads 36. The punching bars 12 pass through the guides 41 carried by the supporting plate 42 of the converter frame so as to guide the punching bars 12 through the twyers 11 as above described for keeping the twyers clean and free to permit the air to freely pass there-through while the machine is in operation.

The lower piston rod 26' is secured at its 70 outer end to a transversely extending bar 43 which supports a plurality of heads 44 to which heads are secured the punching bars 12, as clearly shown in Fig. 4. These punching bars 12 pass through the guides 41 carried by the converter 1, the guides of the lower punching bars being arranged in staggered relation with respect to the guides 75 for the upper punching rod. The transversely extending bar 43 travels in the lower 80 track 33 as clearly illustrated.

It is necessary to employ different series of punching rods in order to prevent too much air coming out of the converter at one time, for the reason that air is bound to escape during the punching operation. It of course is obvious, that if all the rods were operated at one time, hardly any air would pass through the converter, while in operation. Therefore, by punching one half of 90 the rods at a time, about one half of the 95 blast is effective.

What I claim is:—

1. A punching device of the class described comprising a frame, said frame provided with an upper and a lower track, a transversely extending bar working in each track, a series of punching bars supported upon each transversely extending bar, each set of punching bars being arranged in staggered relation, and means for reciprocating 100 said punching rods upon said frame.

2. A punching machine of the class described comprising a frame, an upper and lower track, a transversely extending bar secured to each track, punching rods secured to each transversely extending bar, the bars carried by the upper and lower transversely extending bars being arranged in alternate spaced relation, means for reciprocating 110 said transversely extending bars upon said track, and guiding means for directing said punching bars into the converter.

3. In combination with a converter provided with twyers, of a frame, a plurality 120 of tracks carried by said frame, a transversely extending bar working in each track, punching bars secured to each transversely extending bar, and said bars working alternately with respect to each other for causing one half of the air blast to remain effective during operation.

4. In combination with a converter provided with twyers, of a frame, a plurality of tracks carried by said frame, a transversely extending bar working in each track, 5 punching bars secured to each transversely extending bar, punching bars carried by one transversely extending bar fitting between the punching bars of the other transversely extending bar, and means for alternately reciprocating the different series of punching bars for causing at least one half of the air blast to remain effective during operation. 10

In testimony whereof I hereunto affix my signature.

HENRY LEFEBVRE.
